UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

PRINTING-PRESS.

1,077,214.

Specification of Letters Patent.

Patented Oct. 28, 1913.

Original application filed June 4, 1910, Serial No. 564,997. Divided and this application filed February 3, 1911. Serial No. 606,383.

To all whom it may concern:

Be it known that I, HOWARD M. BARBER, a citizen of the United States, and resident of Stonington, in the county of New London and State of Connecticut, have invented a new and useful Improvement in Printing-Presses, of which the following is a specification.

The object of this invention is to provide mechanism for feeding slip sheets into position to be combined with the printed sheets as they are delivered.

This invention is shown in connection with a multicolor printing press provided with a reciprocating delivery, but it is obvious that the invention could be applied in connection with printing presses of other types and in connection with sheet deliveries of various types.

20 A practical embodiment of the invention is represented in the accompanying drawings in which,

Figure 1 is a part diagrammatic and part longitudinal central section through so much of a multicolor printing press as will give a clear understanding of the location, construction and operation of the invention. Fig. 2 is an enlarged detail section, showing the operative connections between the several parts at one side of the machine. Fig. 3 is an enlarged detail view, showing the operative connections between the several parts at the other side of the machine. Fig. 4 is a detail side view of the cam which 35 controls the mechanisms for opening and closing the grippers on the main sheet feed cylinder and for opening and closing the grippers on the slip sheet feed cylinder, and Fig. 5 is a similar view of the mechanisms 40 for opening and closing the grippers on the slip sheet feed cylinder.

The main frame is denoted by 1, in which frame are mounted the shafts 2, 3, 4, 5, of the plate cylinders 6, 7, 8; 9, and the shaft 10 of the impression cylinder 11. The impression cylinder 11 is provided with a set of grippers 12 arranged to be opened at the proper time in the usual manner, by the stationary cam 13, for receiving the sheets 50 from the grippers 14 on the main sheet feed cylinder 15. This cam 13 also opens the grippers 12 at the proper time to deliver the main sheets from the impression cylinder

11, after they have been printed, to the grippers 16 on the transfer roll 17. Suitable inking mechanisms 18, 19, 20, 21, are provided for supplying ink to the plate cylinders 6, 7, 8, 9. A second transfer roll 22 is provided with a set of grippers 23 arranged to be opened at the proper times to receive first a sheet from the set of grippers 24 on the slip sheet feed cylinder 25; second, to receive a printed sheet from the grippers 16 of the first transfer cylinder, and third, to permit the two superposed sheets to be 60 fed to a sheet delivery device, that shown herein being a reciprocating flat sheet delivery device 26, of well known and approved form. The upper and lower guides for this reciprocating flat sheet delivery device are denoted by 27, 28, the inner ends of which guides are located in close proximity to the second transfer roll 22.

The main sheet feed table is denoted by 29 and the slip sheet feed table is denoted by 75 30. A sheet stop 31 is provided for the table 29 and a sheet stop 32 is provided for the table 30.

A stud shaft 33 is mounted in the end frame 1, which stud shaft may be driven at 80 the desired speed from any suitable source of power, not shown herein. The impression cylinder 11 is provided with a spur gear 34 fixed thereon and a loose spur gear 34*, which loose gear is driven by a spur 85 gear 35 fixed to the shaft 33. The main sheet feed transfer cylinder 15 is driven from the impression cylinder 11, through the spur gears 34*, 36. The first transfer reel 17 is driven from the impression cylinder 11, through the gears 34, 37. The second transfer reel 22 is driven from the shaft 33 through the spur gears 35, 38. The slip sheet feed cylinder 25 is driven from the second transfer reel 22, through the 95 spur gears 39, 40. The sheet forwarding roll 41 is driven from the second transfer reel 22, through the spur gears 39, 42. The tape carrier roll shaft 43 is driven from the second transfer reel 22, through the spur 100 gears 39, 44, 45. The sheet forwarding roll 46 is driven from the shaft 43, through the spur gears 45, 47. The cam shaft 48 is driven from the second transfer reel 22, through the spur gears 38, 49. The slip 105 sheet feed roll 50, which co-acts with the

cylinder 25, is driven from the cylinder 25, through the spur gears 40, 51.

A fixed cam 52 is arranged to open the grippers 16 on the first transfer reel 17, for receiving the printed sheets from the set of grippers 12 on the impression cylinder 11, said cam being also arranged to open the grippers 16 for transferring the sheets from the first transfer reel 17 to the grippers 23 of the second transfer reel 22.

A fixed cam 53 is arranged to open the grippers 23 on the second transfer reel 22, first for receiving a slip sheet from the grippers 24 on the cylinder 25, and second for receiving a printed sheet from the grippers 16 on the first transfer reel 17. A fixed cam 54 is arranged in position to open the grippers 23 for permitting the superposed printed sheet and slip sheet to be fed to the sheet delivery device 26.

The mechanisms for controlling the opening and closing of the grippers 14 on the main sheet feed cylinder 15 and the grippers 24 on the slip sheet feed cylinder 25 are controlled from a cam 55 on the impression cylinder shaft 10, which mechanisms are constructed, arranged and operated as follows: The shafts of the grippers 14, 24, are respectively provided with tumblers 56, 57, to which are applied springs 58, 59. These tumblers 56, 57, are operated upon at the proper times by being carried by the revolution of their cylinders 15, and 25, over pins 60, 61, and 62, 63, respectively attached to the opposite ends of levers 64, 65, which work on fulcrum pins 66, 67. These pins 60, 61 and 62, 63 are movable by said levers 64, 65, into and out of the path of the tumblers 56, 57, respectively. The lever 64 is rocked at the proper times by a lever 68 mounted on the fulcrum pin 69, one arm of which lever is engaged with the cam 55. The lever 65 is similarly rocked at the proper times by a lever 70 mounted in suitable bearings 71, 72, one arm of which lever is engaged with the said cam 55. The parts are so timed with respect to each other that the grippers 14 on the cylinder 15 and the grippers 24 on the cylinder 25, will be opened to receive their respective main sheets and slip sheets every two revolutions of these cylinders, which is every revolution of the impression cylinder 11. The parts are also so timed that the grippers 14 will be opened to deliver the main sheets to the grippers 12 on the impression cylinder 11, every two revolutions of the cylinder 15. The grippers 24 will also be opened every two revolutions of the cylinder 25 for delivering the slip sheets to the grippers 23 on the second transfer reel 22.

A cam 73 on the shaft 48 controls the operation of the stops 31, 32, as follows: A spring-pressed rocking lever 74 is pivoted

at 75, which lever is provided with a stud 65 or roller 76, engaging the cam 73. A rod 77 connects the lever 74 with an arm 78 fixed to the shaft 79 of the stop 31. Another lever 80 is pivoted at 81 and is provided with a stud or roller 82 engaging the cam 70 73. A rod 83 connects this lever 80 with an arm 84 fixed to the shaft 85 of the stop 32. These parts are so timed that the stops 31 and 32 will be swung up into position and hold the main sheets and the slip sheets in 75 position until their advance edges are to be engaged by the grippers 14 and 24 respectively.

A sheet guide 86 is mounted on a cross-bar 87, which sheet guide is located in position to guide the printed sheets around the first transfer reel 17. Another sheet guide 88 is mounted on a cross-bar 89 in position to direct the slip sheets from the cylinder 25 to the second transfer reel 22.

It is to be understood where the terms "cylinder" or "reel" are used, that I intend to cover any operative device for carrying the sheets through the prescribed paths. It is also evident that various changes might 90 be resorted to in the construction, form and arrangement of the several parts without departing from the spirit and scope of my invention.

In operation, the sheets to be printed are 95 fed from the table 29 to the cylinder 15 and are fed therefrom to the impression cylinder 11. After the sheet has been printed, it is delivered from the impression cylinder 11 to the first transfer reel 17. In the 100 meantime a slip sheet has been fed to the cylinder 25 and this cylinder 25 will feed the slip sheet to the second transfer reel 22 just before the printed sheet is fed thereto from the first transfer reel 17. This second 105 transfer reel will then transfer the slip sheet together with the printed sheet on top of the same to the sheet delivery device in position to be delivered to any predetermined point.

An automatic means is thus provided for feeding slip sheets into position to be associated with the printed sheets as they are delivered from the printing mechanism.

The parts shown and described but not 115 claimed herein, form the subject-matter of my co-pending application filed June 4, 1910, Serial No. 564,997, of which this is a division.

What I claim is:

A sheet delivery device arranged to deliver the sheets printed side up, a sheet printing mechanism including an impression cylinder arranged to receive and deliver one sheet at each revolution of the 125 cylinder, a printed sheet transfer device comprising two reels, one arranged to receive the printed sheet directly from the

impression cylinder and transfer it to the second reel and the other arranged to transfer the sheet to the delivery device, and a sheet feeding cylinder arranged to feed a sheet to the impression cylinder every second revolution of the sheet feeding cylinder.

5 In testimony, that I claim the foregoing

as my invention, I have signed my name in presence of two witnesses, this first day of February A. D. 1911.

HOWARD M. BARBER.
